ELECTROMAGNETICALLY OPERATED PHOTOGRAPHIC SHUTTER WITH FLASHLAMP SYN-CHRONIZER

Wilbur G. Hill, Binghamton, N. Y., assignor to General Aniline & Film Corporation, New York, N. Y., a corporation of Delaware

Application May 6, 1953, Serial No. 353,390

10

1 Claim. (Cl. 95—11.5)

This invention relates to photoflash synchronizing arrangements for photographic shutters and more particularly to automatic time delay operation of shutters in connection with flash bulb ignition.

Photographic flash bulbs consist of a glass vessel generally containing oxygen and aluminum or magnesium in the form of thin wire or foil. An igniter usually coated with a combustible substance is provided and the combustion of the aluminum or magnesium is initiated by the fusing of the igniter due to electrical current flow supplied from any convenient source, such as a dry battery or a transformer.

A certain time elapses between the instant when the circuit is closed and the ignited aluminum or magnesium reaches the peak of its light emission. This time lag varies as to the type of flash bulb. The most commonly used bulbs have a 20 millisecond lag and certain others have a 5 millisecond lag. This time delay may vary between bulbs of the same manufacture and occasionally bulbs which should have a 20 millisecond lag may require more or less time as the case may be.

Aside from the characteristics of the bulbs, the condition of the ignition current source and the contact resistance of the switch will also influence the time delay for peak light efficiency. An older battery will not provide adequate current for instantaneous fusing of the igniter and the switch contacts may have sufficient resistance to lower the current for most efficient ignition.

Existing synchronizing arrangements require adjustment by mechanical means to permit the efficient use of bulbs with different time "lag" or ignition duration. Since the flash bulb lag from the time of closing the circuit to peak intensity is greater than the start of opening of the shutter leaf to maximum opening, the flash contact has to be closed before the shutter is open.

Flash units, synchronized with camera shutters and built within the shutter housing generally operate by a master control element which, after being released, closes the electrical circuit to the bulb, is then delayed or held back by mechanical retarding devices for a predetermined length of time, thereafter being released to actuate the shutter.

Use has also been made of electromagnetic devices such as a solenoid which, after being energized by the flash circuit switch, releases the shutter operating mechanism. However, in either case, the closing of the flash circuit and the timing of the release of the shutter mechanism is controlled by a mechanical delay apparatus which is preset to a predetermined time delay. As a rule, this cannot be varied except in certain of the more expensive cameras which have a selectable delay of either 20 or 5 milliseconds so as to accommodate both types of the most commonly used flash bulbs.

It is the primary object of this invention to provide automatic synchronization of the shutter mechanism for flash bulbs irrespective of their inherent time lag.

It is a further object of the invention to effect automatic adjustment of the shutter release mechanism and

2

to this end means are provided for controlling the release in accordance with the electrical characteristics of the flash bulb.

A particular feature of this invention is that the time delay of shutter operation requires no preset mechanical retard mechanism but is controlled by the electrical current utilized for the ignition of the bulb.

Another feature of this invention is that remote electrical operation of a flash synchronized camera may easily be effected in a simple manner without necessitating other than the flash circuit for interconnection between the flash bulb and the camera.

Other objects and features will be apparent from the following description of the invention, defined in particularity in the appended claim, and taken in connection with the accompanying drawings in which:

Fig. 1 is a view, partly in cross section, of a conventional between-the-lens type shutter, in primed position, incorporating the flash synchronizing arrangement;

Fig. 2 is a similar view showing the pertinent component elements of the shutter at the instant of exposure release;

Fig. 3 is a similar view showing the same component elements nearing the end of the exposure period;

Fig. 4 is a perspective view of the movable contactor of the flash ignition switch;

Fig. 5 is a schematic circuit of the flash bulb, the switch, the electrical current source and the actuating electromagnet;

Fig. 6 is a modification of the flash synchronizing arrangement applied to a conventional type of shutter;

Fig. 7 is a curve showing the relationship between the magnitude of the ignition current versus time duration of a conventional 20 millisecond flash bulb;

Fig. 8 represents a curve of light intensity versus time duration of a flash bulb having the current characteristics of Fig. 7;

Fig. 9 is a curve showing the magnitude of the ignition current versus time duration of a conventional 5 millisecond bulb, and

Fig. 10 is the corresponding light intensity versus time duration curve of a flash bulb having the current characteristics of Fig. 9.

Referring to the figures, the type of shutter shown in the drawings is chosen, by way of example, to illustrate the modifications required in applying the flash synchronizing arrangement in accordance with the invention. It will be seen that such modifications may easily be made in other types of shutters, without interfering with the primary function thereof.

In all shutters having built-in flash synchronization a switching element must be provided which is actuated upon shutter release so as to complete the circuit between the flash bulb and the particular source used for its ignition. This switching element may be connected to any desired moving part of the shutter. However, it is standard practice to use the master member which controls all the interacting components of the shutter in shutters which are pretensioned for operation. Since, as far as the shutter elements are concerned, only the master member plays a part in the flash synchronization arrangement in accordance with the invention, it is sufficient, for the sake of simplicity, to show only certain of the basic elements of the shutter which are related to the master member. The rest of the shutter mechanism, such as the shutter blade ring, the exposure time device, etc. have accordingly been omitted.

As seen in the various figures, the shutter comprises the casing 12 which houses all the elements, the shutter actuating or master member 13, which is tensioned by the spring 14 when the manual lever 15 which extends from the casing 12 is moved in a clockwise direction. A

catch and release mechanism for the member 13 is provided, consisting of the pawl 17 pivoted over the stud 18, having a toe 19 which is operatively interconnected with the release lever 20 pivoted over the stud 21.

The master member 13 has various projections and notches for the control of diverse component elements of the shutter. Of these, the projections 23 and 24 are adapted to function in connection with the flash synchronizing operation, as will hereinafter be more fully described.

The operation of the shutter as to exposure opening is not related to the invention. Consequently, it will suffice to indicate that the shutter leaves 26 are opened and closed when the master member engages the bell crank 27. This occurs when the lever 20 is depressed so that the pawl 17 is disengaged from the notch 25. Figure 3 shows the beginning of the exposure when the shutter leaves 26 are partly open.

As seen in Figures 1-3, within the shutter casing is an electromagnet or solenoid 30, the plunger arm 31 of which engages the latch 32 which is pivoted over the stud 33. A spring 34 within the solenoid 30 urges the plunger 35 outwardly so as to position the latch 32 away from the projection 23 of the master member 13 when the solenoid is not energized. A switch for the flash ignition comprises the insulated stationary contact 40 and a moving contactor 41. As seen in Figure 4 this is pivoted over the stud 42, extending from the casing 12 and is biased by the spring 43 so that it will return to neutral position after it has been moved, irrespective of the direction.

A socket 45 extends from the casing 12 and holds an insulated bushing 46 which carries the contact 47. The winding 29 of the solenoid 30 is in series between the contacts 40 and 47 and the casing provides the common terminal of the flash circuit. As seen in Fig. 6, the flash bulb attachment connects with the shutter by means of a suitable plug 48 which fits into the socket 45 and has an insulated prong which engages the contact 47. In this manner, the battery and the flash bulb 50 are placed in series in the circuit as shown in the simple diagram of Fig. 5. The ground connections indicated represent the casing 12.

Reference should now be had to Figs. 7, 8, 9 and 10. These represent the characteristic curves of two types of flash lamps. It is seen that both types of lamps, irrespective of their time lag characteristics, reach peak light intensity approximately at the time when the current in the igniter circuit ceases. In other words, just about the time when the current, which rises steeply to a definite maximum value and is maintained for a definite time duration, falls to zero the peak intensity of light is reached. Whether the flash bulbs have a 20 millisecond lag or only a 5 millisecond lag this condition holds true.

Now then, in accordance with this invention, use is made of this characteristic by providing means which retard the shutter operation until the ignition current falls to zero. In this manner, automatic synchronization is effected with any type of flash lamp having the above described characteristics. The simple electromagnetic mechanism as shown performs this function.

Considering the sequence of operation, in Figure 1 the shutter is seen primed, ready for release. It is assumed that a flash bulb and a battery are connected in the circuit in the conventional manner. Now, when the lever 20 is depressed, the master member 13 is released and, powered by the spring 14, will move in a counterclockwise direction. As this occurs, the contact 41, moved by the projection 24, engages the stationary contact 40 and the ignition circuit is closed. Current through the winding of the solenoid 30 actuates the plunger 35 which in turn moves the latch 32. By the time the master member travels a small fraction, it is arrested by the latch 32 which engages the notch formed by the projection 23.

However, as pointed out before, at the instant, nearing peak light intensity, the current drops to zero so that the solenoid 30 is again deenergized, positioning the latch 32 to disengage the projection 23 and the master member 13 is free to complete its shutter operation. The latter condition is shown in Figure 3.

It will become evident that by holding the master member, after release thereof, until current flow in the flash ignition circuit substantially ceases, automatic synchronization is effected irrespective of the time lag which the flash bulb inherently possesses. The longer this lag, the longer the solenoid 30 becomes energized and correspondingly the master member 13 is held back for a longer time period. On the other hand, with flash bulbs of shorter time lag, the hold back time of the master member becomes shorter. In practice, this will be effective for flash bulbs having a time lag of 5 milliseconds or more which is within the mechanical inertia limits of the component elements.

Without utilizing a flash lamp, the shutter functions in a normal manner without retarding the master member after the release lever 20 is depressed, there being no circuit completed to the solenoid. This remains deenergized so that the latch 32 remains stationary in the off position and will not engage the projection 23 of the master member 13.

The modification shown in Fig. 6 is based on the same principle except that the shutter release and retard mechanisms are combined into one operating unit. The notch 25 and the projection 23 of the master member 13 are so displaced as to be disengaged for the releasing and subsequently engaged for the retarding operation, by the actuating lever 51. The latter is of elongated shape; it pivots over the stud 52 and at one end extends into a detent 53 which is engaged by the plunger arm 31 of the solenoid 30. At the other end, the lever 51 is formed into a latch 54 adapted to engage the projection 23 when pulled down by the solenoid 30. A spring 56 biases the lever 51 into position to engage the notch 25 of the master member 13, and also performs the function of the spring 34, incorporated in the solenoid 30 in the structure shown in Figs. 1, 2 and 3.

The release lever 20 is pivoted on the stud 21 and has a cam portion 57 which engages the latch end of the lever 51 so as to lift the latter and thereby move the detent portion 53 away from the notch 25. The spring 59 provides for the return of the release lever 20 to inactive position.

Upon priming the shutter by moving the lever 15 and thereby the master member 13 against the spring 14, the engagement of the detent 53 of the lever 51 with the notch 25 will hold the master member 13. The release of this engagement may be effected either electrically by the solenoid 30, upon being energized by current from the battery 49, or manually by the release lever 20, as the case may be. When flash exposure is to be used the circuit for actuating the solenoid 30 may be completed by a simple switch incorporated into the flash bulb assembly. This is shown by the spring contact 58 within the casing 60 of the flash bulb 50. A manual push button 61 affixed to the spring contact 58 when depressed effects engagement with the shell 62 of the flash bulb 50, thereby completing the circuit from the battery in series with the igniter 63 over the leads 64 and 65, through connector 48 to the solenoid 30. As this occurs, the plunger arm 31 is pulled in, the detent 53 is disengaged from the notch 25 and the master member 13 is free to move in counterclockwise direction. The lowering of the detent 53 of the lever 51 simultaneously raises the other end of this lever so that the latch 54 will engage the projection 23 after the master member 13 has moved a small distance. Thus, the master member 13 is retarded until such time as the solenoid is deenergized. The latch 54 of lever 51 is then moved out of engagement with the

projection 23 by the spring 56 and the master member is free to complete the exposure operation.

As stated before, the current flow abruptly ceases the instant before peak light intensity of the flash bulb, so that the master member 13 is retarded only until there is no current flow in the circuit. The flash synchronization feature in the modification described above is the same as in the shutter illustrated in Figs. 1, 2 and 3 but, in addition, the release function may also be effected by the current in the circuit. This is particularly advantageous when flash bulbs are placed at a distance from the camera so that shutter operation may be controlled remotely without any other electrical interconnection than normally necessary for flash light operation.

When the shutter is used without flash ignition, the manual release lever 20 provides for normal operation. It should be noted that the cam portion 57 of the release 20 is so dimensioned that it will lift the lever 51 sufficiently to disengage the detent 53 from the master member 13, but not as far as to cause the latch 54 to engage the projection 23. In other words, in ordinary, manual use of the shutter, no retard of the master member 13 is effected. Only when the lever 51 is operated by the solenoid 30 is the displacement such as to provide engagement of the latch 54 with the projection 23 and assure delayed opening of the shutter until the flash bulb has reached near peak light intensity.

I claim:

In a photographic shutter, a tensionable master member having a notch and a projection spaced therefrom, a piv-

5
